UNITED STATES PATENT OFFICE.

JOHN S. YOGERST AND WALTER M. WENCK, OF ST. CLOUD, MINNESOTA, ASSIGNEES, BY
DIRECT AND MESNE ASSIGNMENTS, OF ONE-HALF TO SAID JOHN S. YOGERST AND
ONE-HALF TO JOHN YOGERST, OF ST. CLOUD, MINNESOTA.

SASH-FASTENER.

1,226,736.

Specification of Letters Patent. Patented May 22, 1917.

Application filed June 10, 1916. Serial No. 102,997.

To all whom it may concern:

Be it known that we, JOHN S. YOGERST, a citizen of the United States, and WALTER M. WENCK, a citizen of Great Britain, both residing at St. Cloud, in the county of Stearns, State of Minnesota, have invented a new and useful Sash-Fastener, of which the following is a specification.

It is one object of the present invention to provide novel means whereby a vertically swinging barrier such as a storm window pivotally or hingedly supported at its upper end, may be held at its lower end away from a support, such as a window frame, and, at the will of an operator, be locked in closed position with respect to the frame or support.

In the accompanying drawings:—

Figure 1 shows the invention in side elevation, assembled with a window frame and a vertically swinging storm window;

Fig. 2 shows the structure in top plan and in the position of Fig. 1, the storm window having been omitted in Fig. 2, and Figs. 1 and 2 showing the parts as they will appear when the lower end of the storm window is swung outwardly;

Fig. 3 is a rear elevation of the fastener, the parts being in the positions which they will assume when the storm window has been swung inwardly into closed position with respect to the window frame or support; and

Fig. 4 is a cross section taken approximately on the line 4—4 of Fig. 3, parts appearing in elevation.

In the accompanying drawings there is shown a support 1 which may be a window frame. The numeral 2 indicates a vertically swinging barrier, which may be a storm window or a blind, such structure preferably being pivoted at its upper end to the frame or support 1, as those skilled in the art will clearly understand without specific delineation.

The fastener preferably is made of metal throughout and embodies an inner arm 3 and an outer arm 4, united by a pivot element 5. On its upper edge, the inner arm 3 is provided with a shoulder 6 which, coacting with the upper edge of the outer arm 4 adjacent the pivot element 5, serves

to maintain the parts 3 and 4 in alinement, when the barrier 2 is swung outwardly, as shown in Fig. 1. In the inner arm 3 adjacent its inner end is fashioned an opening 7 which may be denominated a keeper. The inner arm 3 is supplied upon its lower edge directly below the opening 7 with a deflecting lip 8. Attached to the support or window frame 1 is a foot plate 9, and by means of a pivot element 10, the inner end of the arm 3 is held to the foot plate 9 for vertical swinging movement. The foot plate 9 is equipped with a shoulder 25 which will be alluded to hereinafter.

The numeral 11 designates an L-shaped bracket which projects laterally from the outer arm 4 near to the outer extremity thereof. Mounted to reciprocate in the bracket 11 and in the outer arm 4 and disposed transversely of the outer arm is a latch 12 preferably in the form of a rod or bar supplied at one end with a handle 14 which may be an eye. The latch 12 is beveled at one end, as shown at 15, so that it may coöperate with the deflecting lip 8 in a manner which will be set forth hereinafter. The latch 12 carries an abutment which may be a cross-pin 16. Surrounding a portion of the latch 12 is a compression spring 17, one end of which engages the outer portion of the L-shaped bracket 11, the other end of which engages the pin or abutment 16. The spring 17 serves to maintain the beveled end 15 of the latch 12 advanced as shown in Fig. 2.

The numeral 18 denotes a hanger comprising a base 19 and a rectangularly disposed wing 20 carrying a hook-shaped finger piece 24. The base 19 of the hanger is supplied with holes 21 adapted to receive securing elements 22 whereby the hanger may be secured to the barrier 2. A pivoted element 23 unites the outer end of the arm 4 with the wing 20 of the hanger for swinging movement in a vertical plane.

When the barrier 2 is swung outwardly at its lower end away from the support 1 as depicted in Fig. 1 of the drawings, the outer arm 4 engages the shoulder 6 of the inner arm 3, the parts 3 and 4 thus standing in alinement to serve as a rigid brace effective to maintain the barrier in the position which

Fig. 1 discloses. When it is desired to move the barrier 2 to a closed position, the arms 3 and 4 are knuckled upwardly in the direction of the arrow A, the arm 3 swinging on the pivot element 10 of the foot plate 9, and the arm 4 swinging on the pivot element 23 of the hanger 18. Such an operation, obviously, will permit the barrier 2 to swing to a closed position with respect to the support 1.

- 10 When the arms 4 and 3 approach a position of alinement, the beveled end 15 of the latch 12 engages with the inclined deflecting lip 8 of the arm 3. By this operation, the latch 12 is pushed backwardly, until the 15 spring 17 is compressed. Ultimately, the beveled end 15 of the latch arrives opposite to the opening 7, the arms 3 and 4 by this time being in vertical, upstanding positions. Then, under the action of the spring 17, the 20 latch 12 is advanced until its beveled end 15 is engaged in the opening or keeper 7. The arms 3 and 4 now are held in alinement and the barrier 2 cannot be moved to an open position.
- 25 When the arm 3 arrives in a vertical, upstanding position, the rear edge of the arm engages the shoulder 25 on the foot plate 9 which is attached to the support or window frame 1. The arm 3, therefore, is rigidly 30 held against rearward swinging movement.

Having thus described the invention, what is claimed is:—

In a device of the class described, a frame-engaging foot plate having an outstanding shoulder; an inner arm pivoted at one end 35 to the foot plate and provided with an opening located within the contour of the arm, the arm having a laterally inclined lip disposed adjacent the opening; a barrier-carried hanger; an outer arm pivoted at one 40 end to the hanger and pivoted at its other end to the inner arm; and a spring advanced latch carried by the outer arm and operating transversely thereof, one end of the latch projecting beyond the outer arm; the arms 45 being foldable into alinement and into engagement with the shoulder, the lip serving to engage the projecting end of the latch thereby to retract the latch, as the arms move toward alinement, and the said end 50 of the latch engaging automatically in the opening when the arms are in alinement.

In testimony that we claim the foregoing as our own, we have hereto affixed our signatures in the presence of two witnesses.

JOHN S. YOGERST.
WALTER M. WENCK.
